Primary Examiner—Celia Murphy
Attorney, Agent, or Firm—Sheridan Ross P.C.[57] **CLAIM**

The ornamental design for a digital video disc and graphics storage sleeve, as shown and described.

DESCRIPTION

FIG. 1 is a perspective view of a digital video disc and graphics storage sleeve showing our new design, the broken line showing of a graphic sheet being for illustrative purposes only and forms no part of the claimed design;

FIG. 2 is a rear perspective view thereof, the video disk also being shown for illustrative purposes only and forming no part of the claimed design;

FIG. 3 is a front elevational view thereof;

FIG. 4 is a right side elevational view thereof;

FIG. 5 is a top plan view thereof;

FIG. 6 is a rear elevational view thereof;

FIG. 7 is a left side elevational view thereof; and,

FIG. 8 is a bottom plan view thereof.

The broken double lines shown around the periphery of the claimed invention in FIGS. 1, 2, 3, and 6 are understood to represent seam lines.
